United States Patent

Des. 236,745
Patented Sept. 9, 1975

236,745

PAVING MACHINE OR SIMILAR APPARATUS

Constancio S. Fuentes, 2520 Everton,
Lancaster, Tex. 75146

Filed Apr. 26, 1974, Ser. No. 464,314

Term of patent 14 years

Int. Cl. D15—04

U.S. Cl. D40—5

FIG. 1

FIG. 2

FIG. 3

FIG. 4

FIG. 5

FIG. 6

FIG. 1 is a perspective view of a paving machine or similar apparatus showing my new design;

FIG. 2 is a top plan view thereof;

FIG. 3 is a rear elevational view thereof;

FIG. 4 is a side elevational view thereof;

FIG. 5 is a side elevational view thereof opposite to that shown in FIG. 4; and

FIG. 6 is a front elevational view thereof.

I claim:

The ornamental design for a paving machine or similar apparatus, substantially as shown.
